No. 687,317.

Patented Nov. 26, 1901.

J. D. KINNEY.

FERTILIZER DISTRIBUTER.

(Application filed Aug. 21, 1900.)

(No Model.)

UNITED STATES PATENT OFFICE.

JOHN DANIEL KINNEY, OF VILLA RICA, GEORGIA.

FERTILIZER-DISTRIBUTER.

SPECIFICATION forming part of Letters Patent No. 687,317, dated November 26, 1901.

Application filed August 21, 1900. Serial No. 27,616. (No model.)

To all whom it may concern:

Be it known that I, JOHN DANIEL KINNEY, a citizen of the United States, residing at Villa Rica, in the county of Carroll and State 5 of Georgia, have invented a new and useful Fertilizer-Distributer, of which the following is a specification.

My invention is an improved fertilizer-distributer; and it consists in the peculiar construction and novel combination of devices 10 hereinafter fully set forth, and pointed out in the claim.

In the accompanying drawings, Figure 1 is a perspective view of a fertilizer-distributer 15 embodying my improvements. Fig. 2 is a detail sectional view of a portion of the hopper, the shoe, the drop-spout, and the furrow-opener. Fig. 3 is a detail perspective view 20 of the shaking-arm for the shoe and the rocking tappet.

In the embodiment of my invention the beam 1 is provided with a standard 2, carrying furrow-opening plow or shovel 3, and to the rear end of the beam are attached the 25 handles 4. A drop-spout 5 is secured on the rear end of the beam, and the operating-wheel 6 is journaled in bearings 7 near the front end of the beam. Said wheel 6 is provided on one side with a concentric series of tappet- 30 pins 8, which project therefrom. A pair of braces 9 connect the handle-bars 4 and the beams, and between the said braces is secured the hopper 10, in which fertilizer is carried. A shaking-shoe 11 is disposed under the hop- 35 per and suspended therefrom by a pair of depending straps or hangers 12, between which the shaking-shoe is pivoted. Said shaking-shoe extends rearward and is inclined downward and discharges into the upper end of 40 the drop-spout 5. To the front end of the shaking-shoe is secured an arm 13, which projects forward therefrom and is adapted to rest upon the uppermost of the series of tappet-pins 8 of operating-wheel 6. A rocking tappet 14 is pivoted to the arm 13 and is provided 45 with a forward-extending arm 15, having on its under side a wear-block 16, which is successively engaged by the tappet-pins 8, and said rocking tappet is provided with a rear- 50 ward-extending arm 17, which is adapted to bear upon the arm 13, as at 18.

It will be understood that when the ferti-

lizer-distributer is in operation the rocking tappet 14 by the engagement of its wear-block 16 with the tappet-pins 8 alternately 55 raises and drops the arm 13, thereby vibrat- ing the shoe 11, and hence fertilizer conveyed to the shoe from the hopper is by the vibratory motion of the shoe delivered to the drop-spout 5 and is dropped from the latter into 60 the furrow in rear of the furrow-opening plow or shovel 3. When the machine is backed or drawn rearward for a few paces, as is necessary from time to time during the operation thereof, as when starting a row, the arm 13 65 rests idly on the uppermost tappets 8 and the wheel 6 is free to rotate rearwardly, the rock- ing tappet 14 turning downwardly at its ends to permit the wear-block 16 to clear the tappet-pins. 70

In order to regulate the quantity of ferti- lizer supplied to the drill, I provide a gage- plate 19, which is secured on the rear side of the hopper by a bolt 20. Said gage-plate has an adjusting-slot 21, in which the bolt 20 op- erates, and the lower end of the gage-plate is disposed between the sides of the shaking- 75 shoe 11. Hence by adjusting the gage-plate vertically the space between the lower side thereof and the bottom of the shaking-shoe 80 will be increased or diminished at will, and hence the quantity of fertilizer discharged from the shaking-shoe may be readily pre- determined.

It will be understood that when the arm 13 85 is in engagement with the tappets 8 of the wheel and the machine is being backed the front end of the shoe 11 is lowered and its rear end raised and in contact with the gage-plate 19, which thus also acts as a gate, said gage- 90 plate and shoe coacting when the machine is being backed to cut off the flow of fertilizer from the hopper 10.

Having thus described my invention, I 95 claim—

In a fertilizer-distributer, the combination with a frame, of a wheel carrying a series of tappet-pins, a hopper supported by the frame, a shoe mounted for rocking movement be- 100 neath the hopper, an arm having one end rig- idly secured to the shoe and its other end nor- mally disposed above the tappet-pins, an ad- justable gate arranged at the rear of the hop- per and normally out of contact with the shoe

to permit free escape of the fertilizer when the machine is drawn forward, a rocking tappet pivoted intermediate of the ends of the arm, and a counterweight carried by the tappet to 5 bear upon the said pins, and thus hold the arm normally out of contact therewith, the forward end of the counterweight being beveled to permit the tappet-pins to ride there-over and trip the tappet when the machine is 10 moved backward and thus allow the free end of the arm to drop onto the tappet-pins, the downward movement of the arm causing the

shoe to be moved upward into contact with the gate cutting off thereby the feed of fertilizer, substantially as and for the purpose 15 specified.

In testimony that I claim the foregoing as my own I have hereto affixed my signature in the presence of two witnesses.

JOHN DANIEL KINNEY.
